UNITED STATES PATENT OFFICE

129,727

DESIGN FOR A HOOD OR SIMILAR ARTICLE

Frank J. Wengen, Milwaukee, Wis., assignor to Eagle Knitting Mills, Inc., Milwaukee, Wis., a corporation of Wisconsin

Application March 3, 1941, Serial No. 99,295

Term of patent 7 years

To all whom it may concern:

Be it known that I, Frank J. Wengen, a citizen of the United States, residing at Milwaukee, in the county of Milwaukee and State of Wisconsin, have invented a new, original, and ornamental Design for Hood or Similar Article, of which the following is a description, reference being had to the accompanying drawing, forming part thereof.

In the drawing:

Fig. 1 is a side elevation of the hood of my present design as it appears when being worn;

Fig. 2 is a rear view of the hood of Fig. 1;
and

Fig. 3 is a top view of the hood of Figs. 1
and 2.

I claim:

The ornamental design for a hood or similar article, substantially as shown.

FRANK J. WENGEN.
